UNITED STATES PATENT OFFICE.

GROVE S. TARBELL, OF COLVILLE, WASHINGTON.

DESIGN FOR A KITCHEN-SPOON.

55,540.

Specification for Design. Patented June 22, 1920.

Application filed February 5, 1920. Serial No. 356,403. Term of patent 14 years.

To all whom it may concern:

Be it known that I, GROVE S. TARBELL, a citizen of the United States, residing at Colville, in the county of Stevens and State of Washington, have invented a new, original, and ornamental Design for a Kitchen-Spoon, of which the following is a specification, reference being had to the accompanying drawing, forming part thereof.

Figure 1 is a top plan view of a kitchen spoon showing my new design.

Fig. 2 is an edge view.

Fig. 3 is a sectional view on the line 3—3 of Fig. 1.

I claim:

The ornamental design for a kitchen spoon as shown.

G. S. TARBELL.
